REFRIGERATION

Bengt Reistad, Stockholm, Sweden, assignor, by
mesne assignments, to Servel, Inc., New York,
N. Y., a corporation of Delaware

Application December 19, 1939, Serial No. 309,943
In Germany December 20, 1938

9 Claims. (Cl. 62—126)

My invention relates to refrigerating apparatus and more especially to an improved evaporator which is particularly well adapted for use in connection with an absorption refrigerating apparatus of the continuously operating uniform pressure type.

Among the objects of my invention is to provide an evaporator constructed essentially of sheet metal parts in which an excellent transfer of heat is obtained between the tubes carrying the refrigerant and the sheet metal parts which support the ice trays. Another object of my invention is to reduce the size of the opening required in the wall of the refrigerator cabinet for the insertion of the evaporator.

Further objects and advantages of my invention will be apparent from the following description, considered in connection with the accompanying drawings, which form part of this specification and of which:

Fig. 1 is a more or less diagrammatic view, partially in cross-section, of a preferred embodiment of my invention;

Fig. 2 is a view partially in cross-section, and on an enlarged scale of a portion of the evaporator shown in Fig. 1;

Fig. 3 is a top view, partially in cross-section, of a portion of the evaporator shown in Fig. 1;

Fig. 4 is a side view, chiefly in cross-section, of the complete evaporator;

Fig. 5 is a top view of a portion of the evaporator illustrated in Fig. 4;

Fig. 6 is a cross-sectional view taken on the line 6—6 of Fig. 4; and

Fig. 7 is a perspective view of the evaporator shown in the preceding figures.

Referring more particularly to Fig. 1, reference character 10 designates a generator which includes a flue 11 surrounded by a jacket 12. A conduit 13 connects the upper part of the jacket with the upper end of a condenser 14. Heat transfer fins 15 are secured along a portion of the conduit 13, thus providing a rectifier. The flue 11 is arranged to be heated by any suitable means, such as the gas burner 16.

The lower end of the condenser is connected to a vessel 17, from the bottom of which extends a conduit 18. The other end of conduit 18 extends upwardly and communicates with a leg 19 of a generally U-shaped evaporator conduit 20. The opposite leg 21 of conduit 20 is connected by a downwardly extending conduit 22 with one end of a second generally U-shaped evaporator conduit 23. The opposite end of conduit 23 com-

municates with a space 24 formed within a gas heat exchanger 25.

The opposite end of space 24 is connected by a conduit 26 with the upper part of a vessel 27. The lower end of an absorber coil 28 is likewise connected to the upper part of vessel 27. The upper end of absorber coil 28 is connected by a conduit 29 with a space 30 formed in one end of gas heat exchanger 25 and separated from space 24 therein by a partition 31. A plurality of tubes 32 connects space 30 with a similar space 33 formed in the opposite end of the heat exchanger and separated from space 24 by a partition 34. A conduit 35 connects space 33 with the end of leg 19 adjacent to the point where conduit 18 communicates with the leg 19. A baffle 36 is located at the juncture of leg 19 and conduit 35 to prevent the flow of liquid from the lower part of the leg into the conduit.

20 The U-shaped evaporator conduit 20 is formed with a non-circular cross-section, such as an ellipse, with the major axis extending in a vertical direction. The legs 19 and 21 are preferably lined with a tubular wire screen 37. Evaporator conduit 23 may be constructed of ordinary tubing having a circular cross-section. Indentations 38 are preferably provided along its lower edge for the purpose of damming up pools of liquid.

25 A member 40 of sheet metal extends around the legs 19 and 21 of evaporator coil 20, as is most clearly shown in Fig. 6. Adjoining edges of the member 40 are secured together in any suitable manner which will place the member under tension around the legs 19 and 21. As is shown, in Figs. 6 and 7 the edges in the member 40 are formed as tongues 41 which are inserted through openings formed in a plate 42 and then bent back so as to draw the edges together, thus placing the member under tension. Member 40 forms an upper shelf 43 and a lower shelf 44 for supporting ice trays. The space above the lower shelf is enclosed by means of the upper shelf and by rear and side plates 45 which extend between the upper and lower shelves and preferably in contact with the conduit 20. These plates may be formed with flanges 46 which are welded or otherwise secured to the member 40. These plates serve to protect the evaporator conduit from possible injury.

30 The space above the upper shelf 43 is enclosed by means of a box-like sheet metal structure 47. For reasons which will appear hereinafter, it is preferable that structure 47 be removable from the remainder of the evaporator. For this purpose brackets 48 are riveted or otherwise secured

to the rear of shelf 43 and tongues 49 are provided on the structure 47 in such a location as to be received by the brackets, thus holding the members together at this point.

A front plate 50 is formed with an opening in alignment with the spaces for receiving the ice trays. Member 50 is preferably formed with in-turned flanges which are removably secured to structure 47 by means of bolts 52. The lower part of member 50 extends below evaporator coil 23 and gas heat exchanger 25 and is bolted to a plate 53 which may be welded to the bottom of the gas heat exchanger. Consequently, member 50 serves to secure the front end of structure 47 to the remainder of the evaporator.

Projections 54 and 55 are arranged within the ice tray compartments. Projection 54 may be riveted to the sides of structure 47, while projection 55 may be welded directly to the side plates 45. These projections cooperate with means carried by the ice trays for prying the latter loose if they become frozen to the shelves.

A conduit 60 communicates with the lower part of the vessel 27 and extends within the outer tube of a liquid heat exchanger 61. The opposite end of conduit 60 is connected to the lower end of a coil 62 wound around flue 11. A conduit 63 connects the upper end of this coil with the upper part of the generator. A conduit 64 connects the lower part of the generator with one end of the outer chamber of heat exchanger 61, while a conduit 65 connects the other end of this chamber with the upper part of absorber coil 28.

A conduit 66 connects the upper part of vessel 17 with one end of a pressure vessel 67, while the other end of this vessel is connected by means of a conduit 68 with the conduit 26.

The evaporator and a portion of the gas heat exchanger 25 is disposed within a refrigerator cabinet 69. One wall of this cabinet is formed with an opening 70 through which the evaporator and heat exchanger are inserted during assembly. Upon assembly, this opening is closed by means of an insulating block 71. In order to maintain at a minimum the heat leakage about the opening 70 it is desirable to have the opening as small as possible. By reason of having the structure 47 removable from the remainder of the evaporator, it is possible to have the opening 70 of such dimensions that it will just permit the passage therethrough of the heat exchanger 25 and the evaporator with the structure 47 removed. Thereafter, the structure 47 and the front plate 50 may be secured in place on the evaporator.

The refrigerating apparatus is charged with a solution of refrigerant, such as ammonia, dissolved in a liquid absorption medium, such as water. After this solution has been placed in the apparatus an inert gas such as hydrogen is introduced under pressure and the apparatus is sealed. When the hydrogen under pressure is introduced it tends to change the cross-section of the evaporator conduit 28 to a circular form. This tendency causes the member 40 to be placed under additional tension, thus still further improving the contact between the member 40 and the evaporator coil, which in turn increases the rate of heat transfer.

The above described device operates as follows:

The application of heat from the burner 16 to the solution of ammonia and water in the generator 10 causes the ammonia to be driven off in the form of a gas, which passes through the

conduit 13 to the condenser 14. A certain amount of water vapor is also formed which passes along with the ammonia. However, the cooling produced by the fins 15 is sufficient to condense most of the water vapor, but not the ammonia. The ammonia gas deprived of accompanying water vapor is cooled in the condenser and liquefied therein. The liquid ammonia flows from the lower end of the condenser through the vessel 17 and conduit 18 to evaporator coil 28. Due to the baffle 36 this liquid is prevented from flowing into the conduit 35 and forms a pool in the conduit 28. A similar baffle is provided at the juncture of leg 21 and conduit 22, in order to prevent flow of liquid refrigerant into the conduit 22 until the depth of the pool is sufficient to cause it to spill over this baffle. Through capillary attraction the liquid refrigerant creeps upwardly in the wire screens 37, thus increasing the area of the liquid available for evaporation.

Hydrogen is introduced into the evaporator coil 28 through the conduit 35. In accordance with Dalton's law the presence of this hydrogen reduces the partial pressure of the ammonia, thus causing the latter to evaporate and absorb heat from the surroundings. This heat flows into the coil 28 chiefly from the member 40 which is in good heat transfer relation therewith. If trays containing water are placed on either of the shelves 43 or 44, heat is rapidly extracted therefrom, thus causing the water to freeze.

Liquid ammonia which spills over the baffle between leg 21 and conduit 22 flows into the evaporator conduit 23 where it continues to evaporate in the presence of the hydrogen. The gaseous mixture of ammonia and hydrogen thus formed flows from conduit 23 into the space 24 in the heat exchanger 25 and thence through the conduit 26 and upper part of the vessel 27 to the absorber coil 28. In the absorber the mixture comes into intimate contact with weak absorption liquid introduced through the conduit 65 with the result that the ammonia gas is absorbed. The hydrogen, which is now weak in ammonia, flows from the absorber through the conduit 29, space 30, tubes 32, space 33, and conduit 35 to the upper part of the evaporator. The heat absorbed by the evaporation of ammonia in the evaporator conduit 23 is taken from the space within the refrigerator cabinet 69, and hence serves to cool this space.

The strong solution formed in the absorber flows therefrom into the vessel 27 from where it passes through the conduit 60 to the coil 62. Here the application of heat vaporizes a portion of the solution and the resulting bubbles serve to lift the unvaporized portion through the conduit 63 to the upper part of the generator. In the generator the ammonia is driven out of solution, as previously described, and by the time the absorption liquid reaches the lower part of the generator it is comparatively weak. This weak solution flows through the conduit 64, heat exchanger 61 and conduit 65 to the upper part of the absorber.

The pressure vessel 67 is provided for the purpose of storing uncondensed ammonia vapors under conditions of high temperature of the cooling medium available for the condenser. This serves to increase the pressure within the system, thus enabling condensation to take place at the higher temperature, as is well known.

In order that the member 40 of the evaporator may be wrapped around the evaporator conduit

20 in the manner described, it is necessary that the vertical dimension of this conduit be sufficient so that enough space is provided between the shelves 43 and 44 to accommodate an ice tray. If this conduit were of circular cross-section, the width of the evaporator would be materially increased. This would mean that the evaporator would not only occupy more space in the refrigerator cabinet, but the opening 70 would have to be wider.

While I have shown one more or less specific embodiment of my invention it is to be understood that this has been done for the purpose of illustration only and is not to be considered as limiting the scope of my invention, which is to be determined by the appended claims.

What is claimed:

1. In an evaporator, a pair of spaced conduits, and a sheet of metal extending around both of said conduits and maintained under tension in contact therewith by the application of internal fluid pressure to the interior of said conduits.

2. In an evaporator, a pair of spaced conduits, and a sheet of metal extending around both of said conduits and having its opposite ends joined together, said conduits being of non-circular cross-section whereby the application of internal fluid pressure thereto deforms the conduits and subjects said sheet to tension.

3. In an evaporator, a pair of spaced conduits, a sheet of metal extending around both of said conduits with the opposite ends of the sheet adjacent to each other, said ends being formed with tongues, and a bar formed with apertures in alignment with said tongues, said tongues extending through said apertures and being bent back for drawing said ends together to thereby maintain said sheet under tension in contact with said conduits.

4. In an evaporator, a pair of horizontally spaced conduits, a sheet of metal extending around both of said conduits and in contact therewith, said sheet providing upper and lower shelves for ice trays, the space above the lower shelf being closed in part by the upper shelf, and a hollow member secured to the upper shelf for enclosing in part the space above said upper shelf.

5. In an evaporator, a pair of horizontally spaced conduits, a sheet of metal extending around both of said conduits and in contact

therewith, said sheet providing upper and lower shelves for ice trays, the space above the lower shelf being closed in part by the upper shelf, a hollow member on the upper shelf for enclosing in part the space above said upper shelf, and a front plate removably secured to said hollow member for removably securing said member in place on said upper shelf.

6. In a refrigerator, refrigerating apparatus including an evaporator, a condenser for supplying liquid refrigerant to said evaporator and means for withdrawing vaporous refrigerant from said evaporator and supplying it to said condenser, said evaporator, said condenser and said means being rigidly secured together in permanent fixed relationship, said evaporator including a pair of horizontally spaced conduits, a sheet of metal extending around said conduits and providing upper and lower shelves for ice trays and a hollow member removably secured to the upper shelf for partially enclosing the space thereabove, a refrigerator cabinet having an opening in a wall thereof, said refrigerating apparatus being secured to said cabinet with said evaporator within the cabinet and with said condenser and said means outside the cabinet, said opening being only of sufficient size to permit the introduction therethrough of said evaporator with said hollow member removed.

7. For use in a refrigeration system, an evaporator including a pair of spaced conduits, a metal wall member having parts disposed about and in thermal exchange relation with both of said conduits, said wall member being urged into good thermal exchange relation with said conduits by the application of internal fluid pressure to the interior of said conduits.

8. For use in a refrigeration system, an evaporator including a conduit and a metal part having a portion disposed about said conduit, said conduit being non-circular in cross section and urged in good thermal transfer relation with said portion by the application of internal fluid pressure to said conduit.

9. In an evaporator, a conduit, a metal part having a portion disposed about and hugging said conduit, said portion and said conduit being so constructed and arranged that they are maintained in good thermal exchange relation by continual pressure from within said conduit.

BENGT REISTAD.
